UNITED STATES PATENT OFFICE.

EMIL LAWRENZ, OF DETROIT, MICHIGAN.

RULING PEN.

Application filed July 19, 1922. Serial No. 576,039.

To all whom it may concern:

Be it known that I, EMIL LAWRENZ, a citizen of the United States, and residing at Detroit, in the county of Wayne and State 5 of Michigan, have invented a new and Improved Ruling Pen, of which the following is a specification.

This invention relates to ruling pens designed to draw lines of indefinite length of 10 the same width throughout, and its object is to provide a device of this character which can readily be cleaned and sharpened, which can be readily adjusted to draw lines of any predetermined width, and which can be 15 easily readjusted should it get out of adjustment.

This invention consists of a ruling pen embodying a pair of blades, one of them of resilient material so tensioned that the 20 blades will normally swing apart to permit cleaning and sharpening, one of the blades having a hole and the other an elongated slot, and a bolt and a nut thereon to press the blades toward each other, the head of the 25 bolt being elongated to pass through the slot in one of the blades and thereafter rotatable to extend across the slot, the outer surface of the slotted blade being notched to receive the bolt head and prevent it 30 from turning.

It also consists in forming the nut of inner and outer parts having conical engaging surfaces to secure the rotation of the inner part by the outer but permitting disengagement to allow relative rotation between the parts of the nut.

It further consists of the details of construction illustrated in the accompanying drawing and particularly pointed out in the 40 claims.

In the drawing, Fig. 1 is a top and Fig. 2 a bottom plan of a ruling pen embodying the present invention. Fig. 3 is a side elevation and section on the line 3—3 of Fig. 45 1. Figs. 4 and 5 are sections on the line 4—4 of Fig. 1 showing the two parts of the nut in two relative positions.

Similar reference characters refer to like parts throughout the several views.

50 While the pen shown in the drawing is provided with a handle 1, it should be understood that the present invention is applicable to ruling pens of every description, including those constituting permanent or replaceable parts of compasses and bow pens. Each pen embodies a base 2 and two blades

3 and 4 rigidly connected to the base, one of the blades being of resilient metal so that it may freely bend at about the point 5 when released to permit the points 6 and 7^a to be 60 cleaned and sharpened. The blade 6 is shown formed with an elongated slot 7 to permit the passage of the head 8 of the bolt 9 and with a recess 10 to receive the head 8 when that is crosswise to the slot 7, as 65 shown in Fig. 2. The recess 10 and the under side of the head 8 are preferably rounded to permit the bolt to swing as the pen is opened or closed.

The blade 4 is formed with a hole 12 to 70 permit the bolt 9 to pass through and on the bolt is a nut formed of two parts 13 and 14. The inner part 13 is threaded on the bolt 8 and is conical and fits the conical bore of the outer part 14 which has a graduated dial 15 so that the distance between the points 6 and 7^a and therefore the widths of the lines can be accurately predetermined. The inner part 13 of the nut may be formed with a slot 16 so that the nut may be adjusted. 75

The method of adjusting this ruling pen is as follows: After the pen is cleaned and sharpened, which can easily be done while the parts are in the position shown in Fig. 3, the blades are brought together until the head 8 slips through the slot 7, after which the bolt is turned until the head is across the slot 7 and rests in the recess or notch 10. The nut is then screwed down until the 80 points 6 and 7^a contact. 85

The user then observes the angular distance between the line 17 on the blade 4 and the 0 mark on the dial 15 and then turns back the nut several turns. The outer portion 14 is then pressed down as shown in Fig. 5 and turned independently of the part 13 the angular distance observed when the points 6 and 7^a contact. The parts are then released so the two parts of the nut again engage, as shown in Fig. 4, after which the nut may be screwed down until the points 6 and 7^a engage, at which position the 0 on the dial 15 should register with the line 17. It is then an easy matter to turn the nut to 90 predetermine the widths of the lines to be drawn. 95

The taper of the part 13 of the nut and of the recess in the part 14 is such that the friction between them is sufficiently great to turn the nut on the screw. It will be understood that the part 13 never touches the 100 105 110

blade 4 and hence there is no friction between them.

Another method of adjusting this pen is to turn the dial to zero position and hold it there while the central portion 13 is being turned by a tool engaging in the slot 16 until the points 6 and 7^a engage.

The details and proportions of the parts of this pen may all be changed by those skilled in the art without departing from the spirit of my invention as set forth in the following claims.

I claim:—

1. In a ruling pen, a pair of blades rigidly connected at their inner ends and having alined apertures, a bolt extending through the apertures in the blade and a nut on the outer end of the bolt, said nut consisting of an inner conical part threaded on

the bolt and tapering toward the adjacent blade and an outer part having a conical recess to receive the inner part and adapted to turn the same when the parts are in engagement.

2. In a ruling pen, a pair of blades rigidly connected at their inner ends and having alined apertures, a bolt extending through the apertures in the blade and a nut on the outer end of the bolt, said nut consisting of an inner conical part threaded on the bolt and tapering toward the adjacent blade and an outer part having a conical recess to receive the inner part and adapted to turn the same when the parts are in engagement, said outer part of the nut being provided with a series of graduations to indicate its angular movements.

EMIL LAWRENZ.
